US00D581111S

(12) **United States Design Patent**
DiPasquale

(10) **Patent No.:** **US D581,111 S**
(45) **Date of Patent:** **** Nov. 18, 2008**

(54) **VACUUM**

(75) Inventor: **Kathy E. DiPasquale**, Baltimore, MD
(US)

(73) Assignee: **Black & Decker Inc.**, Newark, DE (US)

(**) Term: **14 Years**

(21) Appl. No.: **29/292,507**

(22) Filed: **Oct. 12, 2007**

(51) **LOC (8) Cl.** **15-05**

(52) **U.S. Cl.** **D32/21**

(58) **Field of Classification Search** D32/21-24,

(57) **CLAIM**

The ornamental design for a vacuum, as shown and described.

DESCRIPTION

FIG. 1 is a perspective view of a first embodiment of a vacuum.

FIG. 2 is a front view thereof.

FIG. 3 is a rear view thereof.

FIG. 4 is a left view thereof.

FIG. 5 is a right view thereof.

FIG. 6 is a top view thereof.

FIG. 7 is a bottom view thereof.

FIG. 8 is a perspective view of a second embodiment of a vacuum.

FIG. 9 is a front view thereof.

FIG. 10 is a rear view thereof.

FIG. 11 is a left view thereof.

FIG. 12 is a right view thereof.

FIG. 13 is a top view thereof.

FIG. 14 is a bottom view thereof.

FIG. 15 is a perspective view of a third embodiment of a vacuum.

FIG. 16 is a front view thereof.

FIG. 17 is a rear view thereof.

FIG. 18 is a left view thereof.

FIG. 19 is a right view thereof.

FIG. 20 is a top view thereof; and,

FIG. 21 is a bottom view thereof.
